UNITED STATES PATENT OFFICE.

IVAN HANKOVICH AND WINKO HANKOVICH, OF EAST CHICAGO, INDIANA.

RAIL-JOINT.

1,216,990.

Specification of Letters Patent. Patented Feb. 20, 1917.

Application filed October 19, 1916. Serial No. 126,580.

To all whom it may concern:

Be it known that we, IVAN HANKOVICH and WINKO HANKOVICH, subjects of the King of Hungary, residing at East Chicago, in the county of Lake and State of Indiana, have invented certain new and useful Improvements in Rail-Joints, of which the following is a specification.

This invention relates to certain new and 10 useful improvements in rail joints.

The primary object of the present invention is to provide a rail joint that is extremely simple in construction and operation and one that will be effectively retained 15 in position when so arranged with comparatively few parts to become damaged or broken.

A further object of the invention is to provide a rail joint of the scarf type in 20 which the tread section of one rail has a projection coöperating with a socket in the tread of an adjacent rail with coöperating locking means carried by the bases of the adjacent rails to obviate the use of joint 25 chairs and similar devices.

With the above general objects in view and others that will appear as the nature of the invention is better understood, the same 30 consists in the novel construction, combination and arrangement of parts to be herein- after more fully described and then claimed.

In the drawing forming a part of this application and to which reference is had herein by like characters designating corresponding parts throughout the several 35 views:

Figure 1 is a side elevational view of a pair of adjacent rails, partially broken away and partially in section to show the inter- 40 locking connection between adjacent rail ends.

Fig. 2 is an end elevational view of the rail carrying the tongue projection with the lower portion thereof shown partly in sec- 45 tion to illustrate one position of the base locking element.

Fig. 3 is a view similar to Fig. 2 with the base locking element in another position.

Fig. 4 is a perspective view of the rail end 50 carrying the tread projecting tongue and the base locking element, and

Fig. 5 is a sectional view taken on line V—V of Fig. 2 illustrating in detail the locking element.

Briefly described, the invention includes 55 complementally formed adjacent rail ends

with a tongue projection carried by the tread portion of one rail adapted for reception in a similarly shaped socket formed in the tread of the adjacent rail end. A 60 tensioned sliding pin or rod is carried by one of the rails adjacent the base portion thereof and is adapted for reception in a socket formed in the adjacent base portion of the adjacent rail. The rail end carrying 65 the sliding pin is constructed to coöperate with a handle carried by said pin whereby the said pin is held in projected locked position with the adjacent rail.

Referring more in detail to the accompanying drawing, the reference numerals 10 and 11 designate adjacent rail ends, the tread portion 12 of the rail 10 being extended to provide a dovetail tongue 13 adapted for reception in the socket 14 70 formed in the tread 15 of the adjacent rail end 11. A slight space is left as shown in Fig. 1 for expansion and contraction of the tongue 13.

The web and base flanges of the adjacent 80 rail ends contact over their entire surfaces as shown in Fig. 1 and means is associated with the adjacent rail-ends at the lower portions thereof to prevent relative movement of the rail ends and consists in providing 85 a longitudinally extending socket 16 at the base of the rail 10 and a similar aligned socket 17 formed in the adjacent rail end 11. The web of the rail 10 is provided with a longitudinally extending slot 18 com- 90 municating with the socket 16 as clearly shown in Figs. 2 to 5, while the forward end of said slot has an angular extension 19 for purposes presently to appear. A sliding pin 20 is received in the socket 16, and when 95 so positioned a handle 21 is threaded thereinto and extends through the slot 18 so that when so positioned, it will be impossible for the pin 20 to be accidentally displaced from the socket 16. An expansion coil 100 spring 22 is mounted in the socket 16 rearwardly of the pin 20 and is adapted to hold the same forwardly projected at all times.

When it is desired to assemble adjacent rail ends, the pin 20 is held retracted in the 105 socket 16 against the tension of the spring 22 and the adjacent rail ends so positioned to enable the tongue 13 to be lowered into the slot 14, and when the sockets 16 and 17 are aligned, the pin 20 may be released so that 110 the spring 22 will force the pin 20 into the socket 17 in the adjacent rail end. When

the pin is moved to this position, the same may be slightly rotated by the handle 21 so that the said handle lies within the angular extension 19 of the slot which will prevent accidental displacement of the pin 20 from the socket 17 and thereby insure a safe lock between the adjacent rail ends.

While the form of the invention herein shown and described is what is believed to be the preferable embodiment thereof, it is nevertheless to be understood that minor changes may be made in the form, proportion and details of construction without departing from the spirit and scope of the invention as hereinafter claimed.

What we claim as new is:

1. A rail joint including complementally formed rail ends, the end of one rail having a dove-tail tongue projection at the tread thereof, a longitudinal socket formed adjacent the base thereof, the said rail having a longitudinally extending slot communicating with said socket over a portion of its length, an angular extension formed at one end of said slot, a spring mounted in

said socket, a pin mounted in said socket against the tension of said spring, a handle extending through said slot and engaging said pin, the other rail end having a dove-tail socket formed in the tread portion thereof adapted for reception of the dove-tail tongue and a socket formed adjacent the base thereof adapted for the reception of the sliding pin, the said handle adapted to be moved into the angular extension of said slot to prevent accidental displacement thereof.

2. A rail joint including complementally formed rail ends, one rail end having a tongue projection at the tread thereof and a spring pressed pin at the base thereof and the other rail having a seat for the reception of said tongue and a socket for the reception of said pin and coöperating means carried by the pin and pin carrying rail to prevent accidental retraction of the pin.

In testimony whereof we affix our signatures.

IVAN HANKOVICH.
WINKO HANKOVICH.
